UNITED STATES PATENT OFFICE.

WILLIAM HAVENS, OF TOPEKA, KANSAS.

VENTILATOR.

Application filed December 19, 1927. Serial No. 240,959.

My invention relates to ventilators more especially intended for railway passenger cars and has for its object the provision of a construction which will automatically adjust itself to the direction of car travel so as to permit the vitiated air to be exhausted from the car interior.

The invention also contemplates means for closing the ventilator when necessary to exclude cold air and also to prevent ingress of snow or rain; while at the same time involving means for preventing ingress of cinders.

The objects and advantages of my invention will all be readily comprehended from the following detailed description of the drawings, wherein:—

Figure 1 is a partial side elevation and partial sectional view of the ventilator.

20 Figure 2 is a partial end elevation and partial sectional view of my improved ventilator.

Figure 3 is a partial plan and partial sectional plan view of my improved ventilator.

25 Figure 4 is a perspective view of one of the deflectors.

My improved ventilator, which is especially adapted for use on railway passenger cars, is intended to be placed on the roof 30 of the car over a suitable opening therein. The ventilator, which has an open bottom, in the particular exemplification, consists of a rectangular frame or housing of larger dimensions at bottom than at top and provided 35 with end walls 10, 10 and a top 11; the ends and sides being shown sloping outwardly toward the bottom at 12 and terminating in the vertically disposed base portions 13 which are adapted to fit onto the roof of 40 the car about a suitable opening therein.

The sides of the ventilator intermediate of the base portions 13 and the top 11, are cut away to provide large openings at 10^a; and both sides are provided with a plurality of 45 transversely disposed partitions 14 arranged parallel with each other in spaced relation to provide the passageways 15 therebetween. These partitions may be in the nature of vertically disposed plates having laterally 50 bent upper and bottom ends or flanges 16 to provide suitable means for securing the same in place.

The two sides of the ventilator are provided with cover members 17, with one longitudinal side of each cover or housing secured to the ventilator top 11 as shown at

18, while the bottom of the outer side (which is disposed beyond the side of the main body of the ventilator) is supported at opposite ends by brackets or straps 19 which latter 60 in turn are secured to the main frame of the ventilator in any suitable manner. The cover members 17, as will be seen in Figure 2, provide open ended housings on the two sides of the ventilator presented in the direction of travel of the car and thus permit air to pass therethrough from end to end.

The sides of the ventilator, within the covers of housings 17, and adjacent to the partitions 14, are provided with a plurality 70 of vertically arranged deflectors 20 and of the general construction more clearly shown in Figure 4; that is to say, the deflectors are arranged to swing on the vertically disposed pivot pins or trunnions 21. The upper end 75 of each pivot pin or trunnion 21 is rotatably supported in place by a suitable bracket 22, while the lower end of each pivot pin is supported by an angle plate 23. The lower ends of all the pivot pins are held in position 80 on the respective angle plates 23 by means of an apertured guide plate 24 extending lengthwise of the ventilator as shown in Figure 3.

The various deflectors 20 are preferably 85 arranged equi-distances apart and, with the exception of the intermediate deflector 25, are each shown provided with an inwardly disposed portion or wing 26 of such width, relative to the distance between the pivot 90 points of the deflectors and the partitions 14, that said wings will engage with either of the adjacent partitions 14 and thereby prevent a positioning of the deflectors parallel 95 with the sides of the ventilator. That is to say, the deflectors 20 are provided with the wings 26 so that the degree of swinging movement of the deflectors will be limited by the wings 26 engaging with one of the adjacent partitions 14, as shown in Figure 3, 100 where it is assumed that the direction of travel of the car on which the ventilator is placed would be toward the bottom of the sheet containing said figure so that the outer air will be rushing lengthwise through the 105 housings 17 in the direction of the arrow.

As the deflectors are all of substantially uniform width and spacing, the position of the intermediate deflector 25, relative to the adjacent partitions 14, is such that proper 110 movement of the intermediate deflector 25 would not be possible if it were provided

with the wing 26 and for that reason I show said deflector 25 provided at bottom with a depending strip or stop member 26^a adapted to engage the bottom of the side of the 5 ventilator to prevent the too far inward swinging movement of the deflector. In other words, the deflectors 20 and 25 are provided with the stops 26 and 26^a, respectively, to prevent them from swinging into a lapping condition or closing position.

It will be understood, of course, that if the car is moving in opposite direction to that assumed in Figure 3, that the air will pass through the housings 17 in a direction 15 opposite to that indicated by the arrow and as a result the deflectors 20, 25 will swing about their pivot points so as to be disposed toward the end of the deflector at which the air leaves the ventilator; the deflectors automatically adjusting themselves to the direction of travel.

Disposed lengthwise of the main housing of the ventilator at a point intermediate the top and bottom thereof, namely at the longitudinal axis of the ventilator, I provide a brace strap or plate 27, see Figure 3; with the ends thereof shown bent downwardly and suitably secured to the end walls 10 of the ventilator. This brace member or strap 25 30 27 is shown provided with a longitudinal slot 28 which is adapted to receive a bolt 29. The bolt 29 also passes through the apertured ends of the links 30, 30 and the bolt is held in place in any suitable manner, as for 35 example by nut 31 which may be held against rotation by a pin 32 passing through the bolt after the nut has been properly screwed into place. The opposite ends of the links 30, 30 are each pivotally connected 40 at 33 to a bracket member 34 secured on the inner side of a door 35; there being a door 35 for each side of the ventilator and each door being of width and length sufficient to close the large openings in the sides of the 45 ventilator. These doors are each pivotally connected at one side thereof, as shown at 36; the pivot pins being supported by suitable brackets as at 37.

The doors 35, 35 are shown in open position in Figure 3 in full lines and may be swung to complete closing position by moving the bolt 29 toward the opposite end of the slot 28 so as to bring the links 30 and their pivot points substantially on dead center as shown in dotted lines in Figure 3.

The sides of the ventilator adjacent to the openings 10^a therein are each provided with a suitable frame or strip 38 arranged in slight spaced relation with the main side 55 wall of the ventilator for the purpose of receiving a suitable screen 39 which is adapted to cover the entire opening in each side wall and prevent ingress of cinders and the like. The screens are intended to be removably held in place in any suitable manner which

will permit them to be slid downwardly out of the frame by flexing the screen, so as to enable cleaning and renewal of the screen wire when necessary.

With my ventilator it is apparent that the deflectors will automatically adjust themselves to the direction of car travel or outer air currents and that with the outer air rushing through the open ended housings 17, 17, an eduction of air from the car interior 75 is induced through passages or channels 15. On the other hand, in the event of severe rains, or the ingress of too much cold air, the ventilator may be closed from the car interior by simply moving the connected 80 ends of links 30, 30 from one end of slot 28 to the other end thereof as previously described.

The construction shown is believed to be the best embodiment of the invention, but 85 structural modifications are possible without, however, departing from the spirit of my invention.

What I claim is:

1. A ventilator of the character described 90 comprising a main housing, open at bottom to the car interior, the two opposite sides of the housing disposed parallel with the direction of travel of the car being each provided with an enlarged opening therein, a 95 plurality of narrow air passages arranged transversely of the sides of the housing and communicating with said openings, open ended air channels arranged in the exterior sides of the housing transversely of said 100 narrow air passages, a plurality of oscillating deflectors arranged in said channels adjacent to said air passages, means for limiting the degree of oscillation of the deflectors, closure members for the openings in 105 the sides of the housing pivotally mounted on the housing interior, and means common to both closure members for simultaneously controlling same.

2. A ventilator of the character described 110 comprising a main housing open at bottom to the car interior, two opposite sides being provided with a plurality of narrow air passages for effecting communication between the housing interior and exterior, open 115 ended air channels in said sides and arranged transversely of said air passages and in communication therewith, deflectors arranged in the channels and pivotally mounted adjacent to the outer ends of said air passages so as to swing laterally, closure means on the housing interior for said air passages, and means common to the closure means for simultaneously controlling same. 120

3. A ventilator of the character described 125 comprising a housing open at bottom to the car interior, the two sides of the housing which are disposed parallel with the direction of travel of the car being provided with a plurality of horizontally spaced narrow 130

- air passages extending transversely for effecting communication between the housing interior and exterior, open ended air channels arranged transversely of the outer ends 5 of said passages, deflectors oscillatingly mounted in said channels adjacent to the outer ends of said passages, screen holding means on the housing interior adjacent to said air passages, closure means pivotally mounted within the housing, and means common to all of the closure means for simultaneously controlling same.
4. A ventilator of the character described adapted to be arranged over an opening 15 comprising a main housing having top and side walls and open at the bottom, two opposite longitudinal sides of the housing being formed with enlarged openings therethrough, a plurality of horizontally spaced 20 partitions arranged transversely in both sides of the housing adjacent to said openings to provide a plurality of air passages, a cover member secured to each of said longitudinal sides of the housing and extending 25 beyond said sides to provide open ended air channels at the outer ends of said partitions disposed transversely of said partitions, a plurality of deflectors pivotally mounted at the outer sides of the housing and within 30 said cover members adjacent to the outer ends of said partitions, and means for limiting the lateral swinging movement of each of said deflectors.
5. A ventilator of the character described 35 adapted to be arranged over an opening and comprising a main housing having top and side walls and open at bottom, two longitudinal sides of the housing having enlarged openings therethrough, a plurality of horizontally spaced 40 partitions arranged transversely of each of said openings to provide a plurality of air passages, a cover member secured to each of said longitudinal sides of the housing on the exterior thereof to provide open ended air channels disposed trans- 45
- versely of said partitions, a plurality of independently movable deflectors pivotally mounted at the outer sides of the housing within said cover members, means for limiting the lateral swinging movement of each 50 of said deflectors, a closure member for each of the openings in the two longitudinal side walls of the housing, each of said members being pivoted at one end to swing laterally, a brace member disposed substantially at the 55 longitudinal center line of the housing interior and provided with a slot extending lengthwise thereof, and a link on each side of said member having one end pivotally connected to a closure member while the 60 other end of each link has slidable relation with said slot and the extent of inward movement of the closure member controlled.
6. A ventilator comprising a rectangular housing open at bottom, two opposite side 65 walls being provided with enlarged openings, a plurality of horizontally spaced and transversely disposed partitions arranged in the outer sides of the housing adjacent to said openings to provide a plurality of narrow air passages communicating with the openings in the side walls, cover members on the housing exterior extending lengthwise of the sides having side openings, adapted to provide open ended air channels disposed 70 parallel with the outer sides of the housing, a plurality of deflectors pivotally mounted in each channel adjacent to the outer ends of said partitions, means adjacent to the pivoted ends of the deflectors whereby the degree 75 of oscillation of said deflectors is controlled, a screen holding frame in the housing adjacent to the enlarged opening in each of said side walls, closure means pivotally mounted at one end on the housing interior 80 for closing said enlarged openings, and means for simultaneously operating said closure means from the interior of the housing.
